UNITED STATES PATENT OFFICE.

OTHO M. OTTE, OF TARENTUM, PENNSYLVANIA.

CLOTHES WRINGER.

Application filed January 18, 1923. Serial No. 613,394.

To all whom it may concern:

Be it known that I, OTHO M. OTTE, a citizen of the United States, and a resident of Tarentum, in the county of Allegheny and the State of Pennsylvania, have made a new and useful Invention in Clothes Wringers, of which the following is a specification.

This invention relates to improvements in clothes wringers and one object is to produce a wringer which is more efficient than the standard wringers with which I am familiar.

Another object is to produce a wringer in which it is impossible for clothes or other articles being wrung to become wrapped around the wringer rolls.

Another object is to produce a wringer which will automatically and progressively compact the articles prior to their entrance through the wringer rolls in such manner that the buttons, if any, on such articles, will be arranged in such position (for presentation to the rolls) as to prevent the same from being torn off or broken.

A further object is to produce a wringer in which the liability to pinch or crush the fingers or hands of the operator is reduced to a minimum.

30 A still further object is to produce a wringer of long serviceable life and one in which the vital parts entering into its make-up may be readily and cheaply renewed.

A still further object is to produce a wringer having the above characteristics which may be manipulated and adjusted in the same manner as the ordinary wringers of today are manipulated and adjusted.

These, as well as other objects which will readily appear to those skilled in the wringer art, I attain by means of the device described in the specification and illustrated in the drawings, accompanying and forming part of this application.

45 In order to embody my invention in a wringer which may be adjusted and operated in a manner as nearly like the ordinary wringer is adjusted and operated has been one aim in designing the wringer illustrated in the accompanying drawings, in which Figure 1 is a side view in elevation of a hand wringer embodying this invention. Fig. 2 is a view in end elevation of the same looking at the gear end of the 50 wringer. Fig. 3 is a view in sectional ele-

vation through the center of one of the wringer end members. In this view, the compression rolls of the wringer are shown in operating position as are also the endless conveyor belts. Fig. 4 is a view similar to Fig. 3, but in this view, the spring tension on the compression rolls has been released, as well as the tension on the endless conveyor belts. Fig. 5 is a view in side sectional elevation showing the relation (in operative position) between the compression rolls, the endless conveyor belts and the idler rollers for the conveyor belts and is taken on line 5—5 of Fig. 1 looking in the direction of the arrows.

The wringer illustrated is provided with end posts or end members 10—10 connected near their bottoms by tie members 11—11 and near their tops by a cross connecting member 12. Clamping devices 13 of ordinary construction are employed for securing the wringer to a wash tub or other suitable support. Instead of vulcanized or soft compression rolls as now commonly used, I employ hard compression rolls 14 and 15. 70 These, as with the present type of rolls are preferably mounted in bearings carried in boxes 16 and 17 confined and slidable within slots 18 formed for that purpose in the wringer end posts.

75 The compression rolls 14 and 15 are preferably formed of cast iron and are preferably made by casting the rolls onto steel spindles. Each of the rolls at its center is grooved as shown at 19 to provide a way 80 or channel for accommodating a bead or ridge on the conveyor belt as will be hereinafter described.

85 The spindles 20 and 21 of the compression rolls are provided with gears 22 of ordinary wringer gear construction which allow adjustment of the compression rolls without unmeshing the gears.

A leaf spring 23 secured at its center to a sliding follower bar 24 has its ends resting upon blocks 25—25 which slide in the end member slots 18 and which bear against the tops of the boxes containing bearings for the upper compression roll 15.

90 Compression roll adjustment screws 26, 105 such as are now commonly employed are threaded through screw blocks 27 confined against rotation within the upper ends of slots 18. The lower ends of adjustment screws 26 bear upon the ends of follower 110

bar 24. A tie plate 28 spans the top of slot 18 and strengthens the top of the wringer end post.

An endless soft rubber belt 29 surrounds the lower compression roll 14 and on opposite sides of the compression roll is supported by idler rollers 30 and 31. These idler rollers at their centers are grooved in the same way as the compression rolls and belt 29 at the center of its inner surface is provided with a ridge or bead 32 adapted to ride within groove 19 of the compression roll and the grooves in the idler rollers. By this means, the conveyor belt is kept in line and caused to run straight.

An endless belt 33 surrounds upper compression roll 15 and on opposite sides of the compression roll is supported by idler rollers 34 and 35, the inner surface of this belt is also provided with a bead 36 adapted to ride within a groove in upper compression roll 15 and grooves in idler rollers 34 and 35.

The idler rollers have reduced ends and these are preferably provided with brass or bronze bearing sleeves 37. The idler rollers are supported so that they may be moved laterally of the wringer end posts or toward and from the compression rolls to vary the tension of the endless belts 29 and 33. The arrangement is such that this is accomplished by means of the screws 26 for varying the spring tension on the compression rolls 14 and 15.

Idler rollers 30, 31, 34 and 35 are mounted within bearing holes formed in support arms 38. The support arms are operatively connected to and depend from adjustment heads 38^a (one for each side of the wringer) mounted on tension screws 26.

The adjustment heads are preferably formed of metal (either malleable iron or steel stampings) and as shown in the drawings, each head consists of a curved top having a flattened central portion 39 provided with a central opening which surrounds an unthreaded portion of adjustment screw 26 and which central portion lies between two collars 40 and 41 secured to the adjustment screw. Sides 42 depend from the top portion of the adjustment head and these sides are provided with horizontally extending slots 43. The upper end of each support arm 38 is provided with a vertically extending slot 44 and pins 45 extend through the horizontally extending slots 43 in the sides 42 of the adjustment head and vertically extending slots 44 in the upper ends of the support arms. The inner side of each support arm adjacent the end post of the wringer is provided with corrugations 46, and reverse corrugations are provided in the adjacent face of the wringer end post. The endless conveyor belts hold the support arms in contact with the wringer end posts and in order to prevent side movement of the support arms 38 each arm is provided with a vertically extending groove 47 within which a dowel pin 48 secured to the wringer end post, lies. The 70 slots allow the support arm to slide vertically on the end posts a limited amount.

The support arms and the adjustment heads form two inverted U structures which straddle the end posts. The support arms 75 are of the same width as the end posts so that they do not increase the overall length of the wringer.

The parts are so proportioned that when the compression rolls are in operative position under the desired tension, support arms 80 38 will have been moved to the bottom of their travel and the endless conveyor belts will be under proper operating tension.

It will be seen that because of the general 85 inclination of the corrugated front and back surfaces of the wringer end posts with which the support arms contact, the support arms in moving downwardly are also caused to move outwardly or laterally of the wringer compression rolls and therefore, the distance between idler rollers 30 and 31 is increased and likewise the distance between idler rollers 34 and 35. As the support arms 90 are moved up along the inclined surfaces, the distance between the sets of idler rollers is decreased and the tension on the conveyor belts is, therefore, lessened.

The length of the slots 43 with relation 100 to the diameter of the pins 45 allows the upper ends of the support arms 37 to move horizontally within the adjustment heads 38^a. The vertical slots 44 are of such length with relation to the diameters of pins 45 that a lost motion connection is afforded between the adjustment heads 38^a and the support arms 38. This allows certain movement of the adjustment screws 26 without moving the support arms and in this manner the compression rolls may be adjusted without affecting the tension on the conveying belts. During non-use of the wringer, it is important 105 that the tension on the conveyor belts be reduced and this may be accomplished by backing off adjustment screws 26 thereby 110 raising support arms 38 and with them the idler rollers. When the idler rollers are raised to the position shown in Fig. 4, the 115 tension on the conveying belts will be sufficiently reduced.

When it is desired to adjust the wringer or place the same in operative position, adjustment screws 26 will be turned down until the maximum compression is obtained between the compression rolls. During this 120 operation, the lost motion in the connection between the adjustment heads and idler roller support arms will be taken up and the idler rollers will be moved downwardly and outwardly to their operation position 125 130

thereby stressing the conveyor belts. If maximum compression of the compression rolls is not desired, the spring tension on the compression rolls may be reduced by 5 backing off the adjustment screws 26 without varying the tension of the conveyor belts. The interlocking corrugations between the idler roller support arms and the wringer end posts hold the support arms 10 in adjusted position during the travel of pins 45 within the elongated slots in the upper ends of the support arms.

The bearing holes 49 for the upper idler rollers are elongated so as to allow movement of said idler rollers away from the lower endless belt. If the hands of the operator pass in between the upper and lower idler rollers, the upper idler roller will yield or move upwardly within the elongated slots allowing the hand to be withdrawn. The movement of the upper conveyor belt tends to yieldingly hold the idler roller on the entering side of the wringer toward the lower limit of its movement in 25 elongated slot 49.

The sides of the elongated slots nearest the upper compression roll are concentric with the upper compression roll. The invention, it will be apparent is applicable to 30 power wringers as well as hand wringers, and the details of construction illustrated may be considerably varied without departing from the spirit of the invention.

Having thus described my invention, 35 what I claim is:—

1. In a wringer having adjustable spring tension compression rolls, four idler rollers arranged in pairs on opposite sides of the compression rolls, an endless elastic belt 40 surrounding each pair of idler rollers and one of the compression rolls, adjustable supports for said idler rollers and means including a lost motion connection for varying the tension of said belts.
- 45 2. The combination with the compression rolls of a wringer mounted in bearings carried in the wringer end posts of means movable vertically of said end posts for varying the roll compression, idler roller

supports having a lost motion connection 50 with said means, rollers carried by said supports on opposite sides of the lower compression roll, rollers carried on said supports on the opposite sides of the upper compression roll and having vertical movement independent of said supports, an endless belt surrounding the lower compression roll and the two lower idler rollers, and an endless belt surrounding the upper compression roll and the two upper idler 60 rollers.

3. In combination with the compression rolls of a wringer, means for varying the roll compression, support arms having a lost motion connection with said means, 65 idler rollers carried by said support arms on opposite sides of the lower compression roll, an endless elastic belt surrounding said idler rollers and said compression roll, idler rollers located on opposite sides of the upper compression roll and carried within vertically elongated slots in said support arms and an endless elastic belt passing around said rollers and the upper compression roll. 70

4. In combination with the compression rolls of a wringer mounted in bearings carried in the wringer end posts, means for varying the roll compression, support arms movable vertically and laterally of the 80 wringer end posts and having lost motion connection with said means, rollers carried by said support arms on opposite sides of the lower compression roll, an endless belt 85 passing around said rollers and the lower compression roll, rollers located on opposite sides of the upper compression roll carried by said support arm and having vertical movement independently thereof, an endless belt passing around said rollers and the upper of said compression rolls and means for holding said support arms in different 90 positions vertically of said wringer end posts. 95

In testimony whereof, I have hereunto subscribed my name this 9th day of January, 1928.

OTHO M. OTTE.
